PLAYGROUND SEESAW

Claude W. Ahrens, West Highway 6,
Grinnell, Iowa 50112

Filed July 24, 1972, Ser. No. 274,462

Term of patent 14 years

Int. Cl. D21—03

U.S. Cl. D34—5 C

FIG. 1 is a side elevational view of the playground seesaw showing my new design;

FIG. 2 is an elevational view of the side of the seesaw opposite to that shown in FIG. 1;

FIG. 3 is an end elevational view;

FIG. 4 is a top view; and

FIG. 5 is a bottom view.

I claim:

The ornamental design for a playground seesaw, substantially as shown.
